UNITED STATES PATENT OFFICE.

JOHN KIEWICZ, OF HYDE PARK, MASSACHUSETTS, ASSIGNOR TO THE REECE BUTTON HOLE MACHINE COMPANY, OF BOSTON, MASSACHUSETTS, A CORPORATION OF MAINE.

DRIVING AND STOPPING MECHANISM.

1,188,941.

Specification of Letters Patent. Patented June 27, 1916.

Application filed September 4, 1913. Serial No. 788,047.

To all whom it may concern:

Be it known that I, JOHN KIEWICZ, a citizen of the United States, residing at Hyde Park, in the county of Suffolk and State of Massachusetts, have invented certain new and useful Improvements in Driving and Stopping Mechanism, of which the following is a specification, reference being had therein to the accompanying drawing.

10 This invention relates to driving and stopping mechanism and more particularly to a means for causing a stoppage of the stitching mechanism at the end of the stitching operation in a buttonhole sewing machine of the type referred to, for example, in my prior Patent 1,021,739, of March 26, 1912. In such prior machine the stitching mechanism is sustained by a so-called movable stitch frame which has one movement 20 to bring the stitching mechanism into or out of operative position, and another movement for feeding the stitching mechanism while operating upon the buttonhole. The first movement, which is a quick movement, 25 is secured by means of a quick-feed shaft, while the slower feed movement of the frame is otherwise secured.

The general operation of this type of machine is that the quick-feed shaft is first 30 connected to its driving mechanism, causing the frame to move quickly forward (after the cutting operation) into proper operative position relatively to the cut buttonhole, whereupon the quick-feed shaft is disconnected from its driving mechanism and the stitching mechanism automatically begins its operation, during which the frame has a slow feed movement as the stitching progresses. As soon as the buttonhole is 35 completely stitched, the rapidly operating stitching mechanism must be automatically thrown out of operation at the proper point, and thereupon the quick-feed shaft is again connected to its driving mechanism causing 40 the frame to quickly return to initial position.

The present invention is shown as applied 45 to effect the stoppage of the action of the stitching mechanism at the completion of the buttonhole. Such stoppage should occur before the quick-feed shaft is allowed to be driven for the return movement of the frame, to prevent accident. The stitching mechanism is driven from a high speed 55 driving shaft which obviously must be

brought to rest at precisely the proper point at the completion of the buttonhole and, moreover, in such position that the needles will be disengaged from the work to permit the stitch frame to be thereupon retracted 60 to initial position.

The present invention has for an object to provide an improved driving mechanism having stopping means for effectively accomplishing these results, and, moreover, in 65 such way as to prevent excessive shock, noise and wear upon the fast rotating parts thus suddenly brought to stop.

Other objects will appear in the herein-after following description.

To the attainment of such objects the present invention consists in the novel mechanisms, combinations, arrangements, details and other features shown and described in the accompanying drawings and specifications. First will be described one form in which the present invention may be embodied and thereafter the novel features will be pointed out in the claims.

In the accompanying drawing forming a 80 part hereof Figure 1 is a right-side elevation of the rear end of a machine embodying this invention, showing the driving shaft for the stitching mechanism carried by the movable stitch frame. Fig. 2 is a partial rear elevation of the parts shown in Fig. 1. Fig. 3 is a partial plan view showing some of the parts of Fig. 2. Fig. 4 is a partial left-hand elevation showing certain parts of Fig. 3. Fig. 5 is a rear elevation 85 showing certain parts of Fig. 3. Fig. 6 is a vertical section taken upon the plane 6—6 of Fig. 1. Fig. 7 is a cross-section of the brake device taken on the plane 7—7 of Fig. 1. 90

The same reference numerals are applied to the corresponding parts in the several figures of the drawings.

Upon the stationary frame 11 of the sewing machine is mounted the movable stitch frame 12 adapted to slide forwardly and backwardly, and carrying the stitching mechanism. The stitch frame is supported on the sliding base 13. The driving shaft 14 for the stitching mechanism is carried in 100 the movable stitch frame. Upon the shaft 14 is a loose pulley 15 and a fast pulley 16 enabling a belt to be shifted from one to the other for driving or disengaging the shaft.

A convenient belt shifter consists of the 110

detachable portion 20 secured to the movable body portion 21 having at its lower end a forwardly and rearwardly extending pin or shaft 22 engaging in bearings 23 fast 5 on the frame 11. A collar 24 secured to the shaft between the bearings is provided with a lug 25 actuated by a spring 26 tending to keep the belt normally upon the fast pulley so that the stitching mechanism is driven 10 unless rendered inoperative in the manner hereinafter described.

The stopping device 30, which is so constructed and connected as to effect both the shifting of the belt and the application of a 15 brake, besides affording a positive stop, consists of a hollow upright portion 31 from which forwardly extends the arm portion 32 secured to a shaft or sleeve 33 so as to permit a swinging of the stop device 30 toward 20 and from the driving shaft 14.

Carried by the portion 31 is a yielding lug 34 adapted to engage a co-operating lug that rotates with the driving shaft. The lug 34 is formed at the upper end of a bolt 25 35 which is slidably upwardly and downwardly in the hollow interior of the portion 31. At the lower end the bolt 35 has a strong spring 36 applied between its head 30 and the bottom of the portion 31, thereby tending to maintain the bolt and the lug 34 35 yieldingly in lowered position. As seen in Fig. 6, the portion 31 is so recessed at 37 as to form a stop determining the lowered position of the lug.

From a hollow hub 40 secured on the driving shaft 14 projects a lug or toe 41 which rotates with the shaft and at times is adapted to be engaged by the yielding lug 34. In Fig. 4 it is seen that the lug 41 is 40 capable of a slight movement in a slot formed at 42 in the periphery of the hub. This slight movement of the lug is circumferential, the lug being provided with an annular portion or sleeve 43 surrounding 45 the entire circular portion of the hub. A strong spring 44 located behind the lug tends to break the shock when the two lugs meet, by permitting a slight yielding.

From the above it will be seen that swinging 50 the stop device 30 toward the driving shaft places the lug 34 in the path of the fast rotating lug 41 causing the lugs to engage and tending to stop the shaft. At the same time it is herein proposed to not only 55 shift the belt but to apply a brake and in such a way as to bring the parts accurately and easily to stopped position with the needles out of the work.

For automatically shifting the belt, the 60 following simple expedient will suffice. Referring particularly to Fig. 2, the lower end of the portion 31 is provided with an inclined projection 48 adapted to engage a similar projection or incline 49 formed on 65 the belt shifter portion 21. When the stop-

ping device 30 is allowed to swing inward for causing the lugs to engage each other the inclined projections 48 and 49 engage, the former rising and forcing the latter laterally to throw the belt shifter and shift the 70 belt from the fast pulley 16 to the loose pulley 15.

A convenient automatic braking device 75 may comprise the brake lever 53 yieldingly supporting a brake shoe 54, a spring 55 being interposed between the two in a manner indicated in Fig. 1 and in cross-section in Fig. 7. The brake lever is shown pivoted at 56 to a fixed bracket 57, and the rear extremity of the brake lever passes into recess 80 58 formed in the stop device portion 31, and into recess 59 in the bolt 35, as indicated in Figs. 1 and 6. When the stopping device swings to operative position, it lifts the brake lever and moves the brake shoe 85 from the position shown into contact with the hub thus partially braking the shaft. When the lugs meet and the bolt rises in the act of stopping the driving shaft, the bolt lifts the end of the brake lever and applies 90 the brake shoe more forcibly to the periphery of the hub 40, thus supplementing the positive stop action of the lugs, and easing the action.

The connections for starting the quick-feed shaft for returning the stitch frame 95 after the stitching is complete to the initial or cutting position are not fully shown, but are partially indicated as follows; a lever 66 shown partly in dotted lines in Fig. 1 100 controls the usual clutch for the quick-feed shaft. This lever 66, or rather the forward part of it 67, is engaged by the lower end of the downward arm 68 rearward rigidly connected with the arm portion 32 of the 105 stopping device 30, so that when the latter is swung into operative position for stopping the stitching, the movement of the arm 68 permits the movement of lever 66 to start the quick-feed shaft and return the stitch 110 frame to initial position. Such movement of the lever 66 is usually effected by a spring. A locking device is shown for preventing 115 such movement of the lever 66 unless the stitching mechanism has been properly and exactly brought to rest. A locking lever or arm 71 is shown loosely mounted on the same shaft 33 already referred to, and extending downwardly therefrom into the horizontal path of an extension 74 formed on the lever 66. When the arm 71 is in the forward position shown, it prevents the lever 66 moving rearward for starting the quick-feed 120 shaft. The lock lever comprises, not only the downward arm 71, but an upward arm 72 resting upon the periphery pulley 16 in such position that it may drop into notch 73 in said pulley when the parts are in the correct stopping position. At such times obviously the arm 71 is free to be swung back- 125 130

ward, thereby permitting lever 66 to be moved for starting the quick-feed movement, while at other times the quick-feed devices are locked against actuation.

5 For controlling the movement of the stopping device 30 between operative and inoperative positions, it may be provided with an extension 77 forward of the shaft 33 with which it turns, and a contact pin 78 10 projecting from the extension which latter is moved upwardly or held upwardly or released to descend by a control pin 79. This control pin may be vertically movable and operated from beneath the base 13, for example, by means of the operating cam or disk which also controls or effects the slow and quick feed of the stitch frame during stitching. When the stitching is completed, the pin 79 descending, permits the extension 15 20 25 30 35 40 45 50 55 60 65 70 75 77 to descend, and permits the stopping device 30 to swing forwardly to bring lug 34 in the path of lug 41.

A spring may be employed for actually causing the forward swinging of the stopping device, thus in Fig. 2 the spring 82 pulls upwardly on the rearwardly extending arm 83 carried on the same shaft 33 as the stopping device.

As an additional security or expedient for accurate stoppage there is shown provided a spring guard 87 pivoted on the stopping device 30 to swing about a vertical axis, a spring 88 serving to press the free or forward end of the guard leftwise. The guard 35 40 45 50 55 60 65 70 75 80 85 87 is intended to coöperate with the hub 40 by reason of the notch 89 in said hub. Normally the spring guard is disengaged and inoperative as seen in Figs. 1 and 3, but when the stopping device 30 is swung forward, the guard is brought against the periphery of the hub, which prevents complete forward movement until the shaft 14 has rotated to the point where the guard may drop into the notch 89, whereupon the stopping device moves fully forward into the position to bring the shaft 14 and the stitching mechanism to rest. The notch has a slanting exit so that the guard causes no interference with the rotation.

50 The arrangement is such that the notch 89 is so spaced on the hub 40 from the rotating projection 41, that the complete forward movement of the stopping device is permitted at a given time, namely, three-quarters of a revolution in advance of the engagement of the projection 41 with the lug 34. This insures uniformity in the action of the stopping mechanism.

Generally the order of operation in bringing the shaft 14 to rest may be as follows: When at the end of the stitching the pin 79 permits the arm 77 to descend and the stopping device 30 to swing forward, the spring 82 comes into play, moving the 55 60 65 70 75 80 85 87 90 95 100 105 110 115 120 125 130 stopping device partially inward. This

may occur at different points in the shaft's rotation. The stopping device moves only partially inward, being restrained by the guard 87 contacting the hub. Momentarily the parts stand in this position until the hub has rotated sufficiently to bring the notch 89 opposite the guard. At this time, which is three-quarters revolution before the final stoppage, the guard enters the notch, thus permitting the stopping device 70 75 to complete its forward swinging. This forward swinging simultaneously throws the belt from the fast to the loose pulley, and applies the brake shoe to the periphery of the hub. During the next three-quarters 80 85 revolution, the shaft being no longer driven, has a natural slowing down tendency. This, together with the drag of the brake, serves to largely overcome the momentum of the parts. Therefore, when finally the 85 lug and projection meet, the speed has been largely reduced, and the blow occurs with but slight force. Immediately upon the projection and lug meeting, they both yield as explained, thus additionally breaking the 90 abruptness of the shock. Immediately the lug 34 commences to yield, it operates through the bolt 35 to forcibly lift the brake lever and thereby more tightly apply the 95 brake to the hub. As it were, the described parts coöperate by consecutive action to substantially bring the shaft to rest practically without shock, noise or injury.

In explanation of the phraseology used 100 in the claims the following further remarks will render the same more easily understood. The shaft 14 together with the fast pulley 16 and hub 40 all rotate together as one member and the whole may be considered 105 as the shaft with portions of conveniently enlarged diameter for coöperation with the other elements. The stop device 30 is non-rotatable in the sense that it is not a part rotating with the shaft, but, on the contrary, it is shiftable to and from operative position. The stop device has a shaft engaging portion adapted to positively engage the shaft at the predetermined stopping point in the shaft's rotation, for example, 110 115 when the needle and work are disengaged. By positively is meant in contradistinction to frictionally. The action of the stop device is not that of a friction brake, but it positively bars further rotation. The shaft 120 engaging portion or lug of the stop device is yielding so as to give to a limited extent when struck by the projection 41 rotating with the shaft. The belt shifter constitutes a shiftable disconnector serving for rendering inoperative the connections to the shaft from a source of power. The disconnector is shifted by connections actuated by the shifting movement of the stop device, so that the shaft is disconnected from power 125 130

before the stop device has engaged the shaft for stopping. The brake lever and shoe constitute a braking means adapted for retarding the shaft's rotation. The braking means is applied by connections actuated by the shifting movement of the stop device so that the shaft is retarded before the stop device engages the shaft. The recess 59 of the yielding portion 34-35 of the stop device, engaging the brake lever 58 constitutes a means whereby the yielding of the stop device serves to increase the braking action upon the shaft. The shiftable guard 87 is for preventing the stop device moving into stop position and this guard is thrown off guard at a predetermined point in advance of the shaft's stopping point by a means controlled by the shaft's rotation, namely, the notched hub 40 rotating with the shaft. The guard 87 is to advantage carried by the stop device, though it might be otherwise mounted. The combination of the above recited elements is such that when the stop device is shifted into stopping position, it thereupon disconnects power and applies the brake and then, after a predetermined period, namely, three-quarters of a rotation, positively engages the shaft to stop it. In the full embodiment of the invention the positive engagement includes not only the engagement of lug 34 by projection 41, but also the increased braking action caused by and proportional to the yielding of the lug 34.

It will thus be seen that a sewing machine driving mechanism has been described attaining the objects and advantages before referred to, and other advantages of the described mechanism will be apparent to those skilled in the art. Since many features of design, arrangement, detail and the like may be varied without departing from the principles disclosed, there is no intention of limiting the present improvement to such features excepting in so far as the same are specified in the appended claims.

What is claimed is:

1. A driving and stopping mechanism including in combination, a rotatable shaft from which operations are effected, a non-rotatable shiftable stop-device having a shaft engaging portion capable of limited yielding and adapted to engage the shaft at a predetermined stopping point in the shaft's rotation, a shiftable disconnector for rendering inoperative the connections to said shaft from a source of power, a braking means adapted for retarding the shaft's rotation, means whereby the stop-device in its shifting movement effects the shifting of the disconnector and the applying of the braking means, and means whereby the yielding of the stop-device under impact serves to increase the braking action upon the shaft; whereby when the stop-device is shifted into

stopping position it thereupon disconnects power and applies the brake and then after a predetermined rotation positively engages the shaft to stop it by impact and increased braking action.

2. A driving and stopping mechanism including in combination, a rotatable shaft from which operations are effected, the same having a projection rotating with it, a non-rotatable shiftable stop-device having a yielding lug adapted to be struck by said projection, a shiftable disconnector as a belt shifter for rendering inoperative the connections to said shaft from a source of power, a braking means adapted for retarding the shaft's rotation, means whereby the stop-device in its shifting movement effects the shifting of the disconnector and the applying of the braking means, and means whereby the yielding of the stop-device lug serves to increase the braking action upon the shaft; whereby when the stop-device is shifted into stopping position it thereupon disconnects power and applies brake and then after a predetermined rotation positively engages the shaft to stop it.

3. A driving and stopping mechanism including in combination, a rotatable shaft from which operations are effected, a non-rotatable shiftable stop-device having a shaft engaging portion adapted to positively yieldingly engage the shaft at a predetermined stopping point in the shaft's rotation, a shiftable disconnector as a belt shifter for rendering inoperative the connections to said shaft from a source of power, a braking means adapted for retarding the shaft's rotation, means whereby the stop-device in its shifting movement effects the shifting of the disconnector and the applying of the braking means, means whereby the yielding of the stop-device serves to increase the braking action upon the shaft, a shiftable guard for preventing the stop-device moving into its stopping position, and means controlled by the shaft's rotation for throwing the guard off guard at a predetermined point in advance of the shaft's stopping point; whereby when the stop-device is shifted into stopping position it thereupon disconnects power and applies brake and then after a predetermined rotation positively engages the shaft to stop it.

4. A driving and stopping mechanism including in combination, a rotatable shaft from which operations are effected, the same having a projection rotating with it, a non-rotatable shiftable stop-device having a yielding lug adapted to be struck by said projection, a shiftable disconnector as a belt shifter for rendering inoperative the connections to said shaft from a source of power, a braking means adapted for retarding the shaft's rotation, means whereby the stop-device in its shifting movement effects

the shifting of the disconnector and the applying of the braking means, means whereby the yielding of the stop-device lug serves to increase the braking action upon the shaft,
5 a shiftable guard carried by the stop-device for preventing the stop-device moving into its stopping position, and means rotating with the shaft for throwing the guard off guard at a predetermined point in advance
10 of the shaft's stopping point; whereby when the stop-device is shifted into stopping position it thereupon disconnects power and applies brake and then after a predetermined rotation positively engages the shaft to
15 stop it.

5. A driving and stopping mechanism including in combination, a rotatable shaft from which operations are effected, a shiftable stop-device having a shaft engaging
20 portion adapted to engage the shaft at a predetermined stopping point in the shaft's rotation, a shiftable disconnector for rendering inoperative the connections to said shaft from a source of power, a braking means
25 adapted for retarding the shaft's rotation, means whereby the stop-device in its shifting movement effects the shifting of the disconnector and the applying of the braking means, a shiftable guard for preventing the
30 stop-device moving into its stopping posi-

tion, and means controlled by the shaft's rotation for throwing the guard off guard at a predetermined point in advance of the shaft's stopping point.

6. A driving and stopping mechanism including in combination, a rotatable shaft from which operations are effected, the same having a projection rotating with it, a shiftable stop-device having a yielding lug adapted to be struck by said projection, a 35 shiftable disconnector for rendering inoperative the connections to said shaft from a source of power, a braking means adapted for retarding the shaft's rotation, means whereby the stop-device in its shifting movement effects the shifting of the disconnector and the applying of the braking means, a shiftable guard carried by the stop-device for preventing the stop-device moving into its stopping position, and means rotating 40 with the shaft for throwing the guard off guard at a predetermined point in advance of the shaft's stopping point.

In testimony whereof I affix my signature in presence of two witnesses.

JOHN KIEWICZ.
